MODULAR PEDESTAL UNIT

John S. Carter, The Forge, N. Lane, Foxton,
Market Harborough, Leicestershire, England

Filed Aug. 27, 1974, Ser. No. 500,848

Claims priority, application Great Britain Feb. 27, 1974

Term of patent 14 years

Int. Cl. D6—99

U.S. Cl. D6—85

FIG. 1

FIG. 2

FIG. 3

FIG. 1 is a top plan view of a modular pedestal unit showing my new design;

FIG. 2 is a side elevational view of the modular pedestal unit shown in FIG. 1; and

FIG. 3 is a perspective view of the modular pedestal unit.

I claim:

The ornamental design for a modular pedestal unit, substantially as shown.
